D8-343. OR D11,228 EX

DESIGN FOR LOCK-FRONT.

Design No. **11,228**, dated June 3, 1879

UNITED STATES PATENT OFFICE.

RODOLPHE CHRISTESEN, OF HARTFORD, ASSIGNOR TO THE RUSSELL & ERWIN MANUFACTURING COMPANY, OF NEW BRITAIN, CONN.

DESIGN FOR LOCK-FRONT.

Specification forming part of Design No. **11,228**, dated June 3, 1879; application filed May 10, 1879.
[Term of patent 7 years.]

To all whom it may concern:

Be it known that I, RODOLPHE CHRISTESEN, of the city and county of Hartford and State of Connecticut, have invented a new and useful Design for a Lock-Front; and I do hereby declare that the following specification, taken in connection with the accompanying photographic illustration, forming a part of the same, is a full, clear, and exact description thereof.

The novel design hereinafter described is adapted to the face of a lock-front, and possesses the characteristic feature of being in the Japanese style of ornament.

As shown in the accompanying illustration, the plate is surrounded by a raised band, *a*, and the latch and lock-bolt mortises by bands *b*. Between the bands *a* and *b* are short bars

c c', which divide the surface of the plate into three panels, *A*, *A'*, and *B*. The ground of the plate presents a mottled appearance, and the end panels, *A A'*, are each ornamented by branches of a shrub, *d*, which bears leaves, buds, and a geometrical flower, and also by a fluted band, *C*. The central panel, *B*, is occupied by a butterfly or similar insect, *e*. The ornamental portions are cast in relief, and an effective appearance thereby produced.

What I claim, and desire to secure by Letters Patent, is—

The Japanese design for a lock-front, substantially as described and shown.

RODOLPHE CHRISTESEN.
